ELECTRICAL SWITCH

Albert J. Collotta, Roslindale, Mass., assignor to Ark-Les Switch Corporation, Watertown, Mass., a corporation of Massachusetts

Application October 9, 1957, Serial No. 689,150

1 Claim. (Cl. 200—44)

This invention relates to rotary electrical switch mechanisms and more particularly to such mechanisms of the key-operated type.

Key-operated rotary electrical switches have many applications today for the control of electrical circuits. A primary concern or requirement of such a switch is that it be economical to produce while at the same time providing reliable operation, adequate safeguard against unauthorized operation, and indication of the status of the electrical circuits controlled thereby. The economic considerations in particular require that such a switch be capable of manufacture without close tolerances by mass production methods.

Accordingly, it is an object of the present invention to provide a novel key-actuated rotary electrical switch, economical to manufacture and reliable in operation.

Another object of the invention is to provide a key-actuated switch having a key which may be removed from the switch actuating member only in one position, preferably the "off" position.

Another object of the invention is to provide a key-actuated switch which provides safeguards against the operation thereof without a suitable key.

The invention provides a key-actuated rotary switch apparatus which may be manufactured by economical mass production methods and one in which the components thereof are easily assembled into a switch mechanism which is operated by a key. A positioning member for the key supports it in such a manner that the key may be inserted and removed at a specific rotary position thereof. The supporting member further is designed to coat with the key-housing and the switch-actuating member to minimize the possibilities of unauthorized operation of the switch.

Further objects and features of the invention will become apparent from the following description of a preferred embodiment thereof, together with the accompanying drawings in which:

Fig. 1 is a side view of the preferred embodiment of the rotary switch with the operating key in place;

Fig. 2 is a rear end view of the switch of Fig. 1;

Fig. 3 is an exploded view of the key-housing, the key-supporting disc, and the switch-actuating shaft, with the latter two being adapted to be assembled into the key housing;

Fig. 4 is a sectional side elevational view of the switch in Fig. 1 with the actuating key inserted;

Fig. 5 is a sectional view along the lines 5—5 of Fig. 4;

Fig. 6 is a sectional view along the lines 6—6 of Fig. 4;

Fig. 7 is a sectional view, similar to the view of Fig. 4 with the key and the switch mechanism rotated 180°;

Fig. 8 is a sectional view along the lines 8—8 of Fig. 7; and

Fig. 9 is a sectional view of a modified construction of the switch actuating shaft.

The general configuration of the switch may be understood with reference to Figures 1 and 2. The switch

2

comprises a housing 10, a threaded mounting structure 12 and an actuating key 14. Electrical connections are made from a common central terminal 16 to one of three terminals 18, 20, 22 by means of a wiper blade mounted on the rotor washer 24. The fourth position of the switch provides an "off" position. The terminals are mounted on an insulating member 26 and the insulating member is secured to the housing 10 by means of a plurality of bent-over projections 28 extending from the housing. The switch mechanism construction is conventional, a spacer washer 30 being mounted between the rotor washer 24 and a detent plate 32. A shaft 34, mounted within the threaded structure 12 and housing 10 coacts with the switch structure to move the rotor washer 24 as determined by the rotation of the key 14.

The shaft 34 may be best seen in Fig. 3. It consists of a tubular member having an extension 36 adapted to coat with appropriate slots in the detent washer and rotor washer such that the switch elements move as a unit with the shaft 34. The tubular portion has a slot 38 cut in it which is adapted to receive the shank of the key 14. A hole 40 is drilled in the tubular portion such that a coaxial recess is provided in the rotatable sleeve 34. Thus, rotation of the shaft 34 is actuated by a member which operates against the edges of the slot 38 which are provided only at the periphery of the shaft 34.

A disc 42 (best seen in Fig. 3) is inserted between the shaft 34 and a radial shoulder member 46 of the mounting 12. The disc 42 is of sufficient thickness to provide support for the key and has a rectangular slot 44 of a width slightly greater than the thickness of the key 14 and of a depth slightly greater than the width of the key shank.

The mounting 12, as best seen in Fig. 3, has a bore of a diameter great enough to receive shaft 34 and disc 42, with a radial shoulder 46 providing a restricted cylindrical aperture and a slot 48 through shoulder 46 in the upper portion thereof. Thus an appropriately shaped key may be inserted through the aperture and slot 48 to rotate the shaft and switch mechanism. The slot 48 may be cut in the shoulder 46 at a point other than "twelve o'clock" if desired. Further, when it is advantageous that the switch design permit the removal of the key 14 at more than one position of the contacts, a plurality of appropriate slots may be cut in the shoulder 46.

The shape of an appropriate key 14 is shown in Fig. 4. The shank of the key as seen in Fig. 4 has a lower surface cut away such that it will coat with the washer 42. This lower surface rides on the bottom of the slot 44 when the key is inserted into the slot 38 in shaft 34. Bits 15 and wards 17 are provided on the upper surface of the key 14, said bits coacting with the edges of the slot 38 to rotate the shaft 34 as the key 14 is turned.

With reference to Figs. 4 through 8, it will be seen that the key must be inserted into the switch in the position as shown in Fig. 4 wherein the edge containing bits 15 and wards 17 passes through slot 48 in shoulder 46. The insertion of the key 14 is limited to the vertical position by the position of slot 48 in shoulder 12 as the shoulder 46 is not rotatable, and to the position of Fig. 4 rather than to the position of Fig. 7 by the presence of flanges 50, 52 on the key handle adjacent the shank and bits 15 on the shank. When the key is properly inserted as in Fig. 4, the shank of the key is supported by the washer 42 as may be seen in Fig. 6. In order to provide an indication of the position of the switch, it is desirable that the key be removable only in one position. With the construction of the key-housing aperture as shown in Figs. 3 and 5, it is obvious that the key could be removed only when in the positions of Figs. 4 or 7. In order to

provide positive identification of the switch position, it is desirable that the key be removable only in the position as shown in Fig. 4. Provision of the disc 42 between the shaft 34 and the housing aperture positions the key 14 such that it cannot be removed in position of Fig. 7, even by tilting it. The disc 42, in its inverted position, assures the engagement of the bits 15 of the key shank against the shoulder member 46 of the housing 12, thus preventing removal of the key in this position.

A modification of the switch actuating shaft 34 is shown in Fig. 9. The hole 40 in the embodiment shown in Figs. 1-8 is drilled to at least a depth equal to the length of the slot 38. In order to obtain additional surface area against which the key 14 may act, the hole 40 may be drilled to a depth less than the length of the slot as shown in Fig. 9. In this manner the key, in rotative action, contacts a slot edge 54 at the periphery of the drilled hole and in addition the slot edge 56 at the base of the hole.

Thus, a simple construction of a key-actuated rotary electrical switch suitable for inexpensive mass production has been provided. In the preferred embodiments, the key may be inserted and removed only when the switch is in a given position (preferably "off"). The disc, provided to securely position the key in the switch, also limits access to the actuating shaft by articles other than an appropriately designed key, thus reducing the likelihood of tampering by unauthorized operation of the switch.

The principles of the invention have been described in relation to the preferred embodiments of a key-actuated rotary switch. It will be understood that while there has been shown and described herein preferred embodiments, the invention is not intended to be limited thereby to all details thereof, and departures may be made therefrom within the spirit and scope of the invention as set forth in the appended claim.

I claim:

A key-operated electrical switch including: a key barrel having a radial shoulder providing an aperture therein for receiving a flat key with at least one bit along one edge of the key shank, said aperture being a circular opening with a rectangular slot extending radially therefrom; a cylindrical shaft rotatably mounted within said barrel and having a slot in one end adapted to receive said key, said shaft being adapted at its other end to operate upon a rotary contact switching means; and means for substantially preventing unauthorized operation of said switch including: in combination, a cylindrical cavity in the center of said cylinder axially coextensive with said slot therein and of same diameter as said circular opening in said radial shoulder, said shaft thus being rotatable only by an instrument acting against edges of said slot provided only at the periphery of said shaft; and a disc rotatably mounted in said barrel between said shaft and said radial shoulder and having a slot of rectangular cross-section of width slightly greater than the thickness of said key and of depth slightly greater than the width of the key shank and bit, said means thus requiring an instrument of predetermined shape to act upon the slot edge in the periphery of said shaft and simultaneously limiting, by operation of the slotted disc, the configuration of the instrument which is permitted to have access to said shaft.
